F. GIRTANNER & C. NILL.

CLEANING ATTACHMENT FOR FURNACE GRATES.

APPLICATION FILED OCT. 20, 1906.

2 SHEETS—SHEET 2.

Fig. 2

UNITED STATES PATENT OFFICE.

FREDERICK GIRTANNER AND CONRAD NILL, OF ERIE, PENNSYLVANIA.

CLEANING ATTACHMENT FOR FURNACE-GRATES.

No. 863,914.

Specification of Letters Patent.

Patented Aug. 20, 1907.

Application filed October 20, 1906. Serial No. 339,829.

To all whom it may concern:

Be it known that we, FREDERICK GIRTANNER and CONRAD NILL, citizens of the United States, residing at Erie, in the county of Erie and State of Pennsylvania, have invented certain new and useful Improvements in Cleaning Attachments for Furnace-Grates, of which the following is a specification.

In the type of traveling grates or furnaces as generally constructed, a side opening is required at the rear of the grate for removal of clinkers and other accumulations, thereby preventing the employment of such grates in a battery of furnaces.

The present invention wholly obviates the side door and supplies the grate with an automatic cleaning and 15 clinker breaking attachment.

The invention combines with the grate a dumping section in the rear thereof adjacent to the bridge wall, whereby ashes, clinkers and the like may be instantly and conveniently discharged, and a cleaning device 20 which is interposed between said dumping section and the grate, thereby preventing choking of the grate and enabling a clear fire to be maintained.

For a full description of the invention and the merits thereof and also to acquire a knowledge of the details 25 of construction of the means for effecting the result, reference is to be had to the following description and accompanying drawings.

While the invention may be adapted to different forms and conditions by changes in the structure and 30 minor details without departing from the spirit or essential features thereof, still the preferred embodiment is shown in the accompanying drawings, in which:

Figure 1 is a longitudinal section of a furnace grate 35 embodying the invention, showing a portion of the bridge wall and boiler. Fig. 2 is a top plan view of the grate. Fig. 3 is an end view of the crushing roller. Fig. 4 is a side elevation of the crushing roller. Fig. 5 is a detail view, showing the mountings for the inner end of the main grate, the supplemental dumping 40 grate being omitted. Fig. 6 is a view of the parts shown in Fig. 5 with the addition of the supplemental dumping grate.

Corresponding and like parts are referred to in the 45 following description and indicated in all the views of the drawings by the same reference characters.

The grate 1 is of the traveling or movable type so as to gradually and continuously advance the fuel from front to rear so as to prevent the giving off of free carbon and to utilize practically all the heat units derived from the fuel.

The grate illustrated is of the chain type and is supported at its ends upon rollers 2 and 3, the upper portion of the grate being arranged to move from front to 50 rear and the grate is moved in the present instance by sprocket wheel 2 on the shaft of the front roller 2.

The grate is mounted upon a frame 4 which in turn is supplied with rollers 5 arranged to travel upon a track or rest 6, whereby the grate may be removed when desired to admit of repairs being readily and conveniently made or for any desired purpose.

In the rear of the movable or traveling grate 1 is arranged a dumping grate 7 adapted to be operated from any convenient point by means of rods or connections 8. The dumping grate 7 is located adjacent 65 to the bridge wall 9 and is in a lower plane than the main grate 1 so as to receive cinders, coke or other matter discharged therefrom and not eliminated by the interposed clearing means.

The automatic cleaning and clinker breaking device 70 arranged intermediate of the main and dumping grates comprises rollers 11 and 12 disposed in parallel relation and located one in advance of and in a higher plane than the other, said rollers being preferably corrugated, fluted or ribbed so as to make positive 75 engagement with the clinkers to crush and break the same and effect positive discharge thereof between the said rollers. The rollers 11 and 12 are mounted upon shafts 13 and 14, the shaft 13 being angular and the shaft 14 round. The rollers 11 and 12 are composed of a plurality of sections which are loosely mounted upon their respective shafts and are arranged to break joint, as indicated most clearly in Fig. 2. The sections or members comprising the roller 12 are loose 80 upon the shaft 14 so as to turn freely and independently thereon, whereas the sections or members of the roller 11 are slipped upon the shaft 13 and mounted so as to turn therewith. Motion is imparted to the shaft 13 and the sections of the roller turned therewith by reason of their mounting or connection. A sprocket 90 wheel 15 is fast to the outer end of the shaft 13 and is connected by sprocket chain 16 with a sprocket wheel 17 fast to the shaft 18 of the outer or front roller 2. The sprocket wheel 15 is of less diameter than the sprocket wheel 17, hence while the roller 2 turns slowly the 95 shaft 13 has imparted thereto a faster speed, with the result that clinkers caught between the rollers 11 and 12 are crushed and discharged between the rollers into the ash pit. Coke and fuel of a size not to be acted 100 upon by the cleaning device pass by the same and are received upon the dump grate and consumed. The sections or small rollers comprising the respective rollers 11 and 12 are preferably hollow and the ends of supporting portions have notches 19 surrounding the openings to provide for a free circulation of air, 105 whereby the rollers and their supporting shafts are kept cool and prevented from overheating.

The fuel is supplied to the front portion of the grate and is gradually advanced thereby into the combustion chamber, the gases being gradually evolved and 110 consumed. The clinkers clearing the rear end of the grate are caught by the positively driven roller 11 and

carried rearward and downward and are crushed in their passage between the rollers 11 and 12.

In the event of it being required, for any cause, to force the furnace, the main grate may be driven at a higher rate of speed in order to throw more fuel upon the dumping grate 7, thereby increasing the fuel surface. Ashes and other accumulations upon the grate 7 may be removed from time to time by operating the rod 8 so as to effect a dumping of the section or grate, 10 whereby the ashes and other matter supported thereby may be discharged into the ash pit.

In order to prevent bending or other injury to the main grate and the rollers 11 and 12 by a hard substance passing between them, it is preferred to mount 15 the roller 12 so as to yield or move away from the roller 11 when a hard clinker or other yielding object comes between the crushing rollers. As indicated, the shafts 13 and 14 of the crushing rollers are mounted in open 20 bearings formed at or near the rear ends of the side pieces of the grate rest, said bearings consisting of slots 22 and 23. The slots 22 and 23 extend inward from the top edge of the side pieces of the grate rest and are upwardly and rearwardly inclined, thereby preventing 25 casual displacement of the crushing rollers. In the event of a hard clinker or other object not readily crushed passing between the rollers 11 and 12, the latter will move away from the roller 11 and admit of the object 30 passing between the two rollers without exerting unusual strain, such as would cause the rollers either to bend or to break. In order to reset the roller 12, that is, to return it to normal position after being moved rearward by a non-crushable object, rods 24 have connection at their rear ends with the terminal portions 35 of the shaft 14 and their outer ends project through the front of the furnace so as to be readily accessible and at all times under observation. Collars 25 are slipped upon the ends of the shaft 14 and the rear ends of the rods 24 are connected to lugs pendent therefrom. So long as the rollers 11 and 12 remain in relative normal 40 position, the outer ends of the rods 24 occupy a predetermined position, but when the roller 12 is disturbed or moved rearward, the same may be known by observing the changed position of the projecting ends of the rods 24, thereby affording the fireman or other attendant 45 an opportunity to return said roller to normal position by drawing upon the outer ends of the rods 24. The roller 12 may be returned automatically to normal position and for this purpose elbow levers 26 may be fulcrumed to the front portion of the furnace and one 50 arm may have connection with the projecting end of the rods 24 and the other arm may be weighted, the

latter being sufficiently heavy to throw the roller 12 back into normal position when moved rearward in the manner stated.

Having thus described the invention, what is claimed as new is:

1. In combination with a furnace grate, means for removing ashes, clinkers and the like, the same comprising an angular shaft at the end of the grate, a series of roller sections mounted upon said shaft to rotate therewith 60 means for turning said shaft, a round shaft, and a series of roller sections loosely mounted upon the round shaft and adapted to have independent rotary movement thereon.

2. In combination with a furnace grate, means for removing ashes, clinkers, and the like, the same comprising 65 co-operating rollers at the rear of the grate, shafts on which said rollers are mounted the rollers being loose on one of said shafts, the shaft nearest to the end of the grate being angular and the roller thereof being mounted to rotate therewith, means for turning said shaft, a dumping grate at the rear of said rollers, and means for dumping the last named grate.

3. The combination with a traveling furnace grate embodying rollers on which the grate proper is mounted to travel, means for turning one of said rollers whereby 75 to effect the movement of the grate, co-operating rotary crushing members formed of a series of rollers and located at the rear of the traveling grate, shafts on which said series of rollers are mounted, one of said series of rollers being revolvable with its shaft, and the other series being 80 loose on its shaft, and a connection between the first named shaft and the traveling grate and adapted to turn such shaft, as and for the purpose set forth.

4. In combination with a traveling grate embodying a front and rear rollers and shafts therefor, the front shaft 85 being provided with a sprocket wheel, two transverse shafts at the rear end of the grate, rollers mounted on each of said shafts, the rollers on one of said shafts being loose thereon and the rollers on the other shaft being movable with the shaft, a sprocket wheel on said last named shaft, and a sprocket chain connection between said sprocket wheels.

5. A furnace grate, comprising a frame, a traveling grate mounted in said frame, said frame being provided at the rear end of the traveling grate with bearing recesses, shafts mounted in said recesses, an operative connection between one of said shafts and the traveling grate, whereby they will move together, a series of roller sections 95 on the shafts at the rear end of the grate, one series of sections being movable with its shaft and the other loose on its shaft, the shaft with the loose sections being movable in its bearings, a rod connected to said shaft and extending forwardly therefrom, and a weighted lever connected to the forward end of said rod, as and for the purpose set forth.

In testimony whereof we affix our signatures in presence of two witnesses.
